EDWARD H. STINES AND WILBUR C. POTTER, OF NEW BRUNSWICK, NEW JERSEY.

ARM FOR KNITTING-MACHINES.

1,399,278.

Specification of Letters Patent.

Patented Dec. 6, 1921.

Application filed February 19, 1919. Serial No. 277,977.

To all whom it may concern:

Be it known that we, EDWARD H. STINES and WILBUR C. POTTER, citizens of the United States, residing in New Brunswick, 5 in the county of Middlesex and State of New Jersey, have invented certain new and useful Improvements in Arms for Knitting-Machines, of which the following is a specification.

10 We have invented an improvement in arms for knitting machines; particularly arms to be mounted on that part of a knitting machine which carries the devices provided to actuate the mechanism for stopping the motion of the machine in case a mishap occurs 15 to the yarn knitted by same.

Such arms bear certain elements engaged by the yarn and maintained in given positions; and upon the yarn becoming broken, 20 knotted or tangled, those elements are moved and the aforesaid actuating devices thereby released; permitting the stopping mechanism to take immediate effect. Our invention resides in such an arm designed with a 25 view to simplify its construction, cheapen its manufacture, and facilitate its location in operative position and its replacement when damaged.

Other objects and advantages of our invention will appear in the following description, 30 taken in connection with the accompanying drawings, which show the best form of our invention now known to us. This disclosure, however, is explanatory only, and we 35 may resort to changes in what is actually shown, within the scope and spirit of our invention, to the full extent of the general meanings of the terms in which the claims appended hereto are expressed.

40 On the drawings:

Figure 1 is a side elevation of an arm for a knitting machine according to our invention; with the elements appurtenant thereto mounted upon it; the arm being attached to 45 said machine;

Fig. 2 is a plan view and Fig. 3 an end view of the arm illustrated in Fig. 1.

The same numerals identify the same parts throughout.

50 In the particular description of our invention we use the numeral 1 to indicate our improved arm in its entirety; and we show this arm effixed to a casing 2, which in practice will be the upper part of a "stop-motion head" for a knitting machine, be mounted on the upper end of the central stem or

shaft thereof. This casing will have an exterior peripheral flange 3, and is usually cylindrical in shape. Hence one end 4 of the arm 1 will be slightly concave to fit snugly 60 against the outside of the casing 2, beneath the flange 3; and it will be furnished with a pair of projections 5, struck up to engage the edge of the flange 3. The arm will have a threaded opening adjacent the concave end 65 4, and the flange 3 will have a similar opening; whereby a fastening member, such as a screw or bolt 6, may hold the arm and flange together. When the screw is made tight the projections 5 will abut the edge of the 70 flange, and the concave end 4 will make contact over its entire face with the outside of the casing 2, and the arm will therefore be firmly retained in place. We may also round the upper edge of the end 4, as 75 shown in Fig. 1, to enable it to fit the fillet between the casing 2 and the lower face of the flange 3. Hence the end 4 and the adjacent portion of the top of the arm may have actual contact with the casing 2 and 80 bottom of the flange at every point, and when the screw 6 is turned up, the end 4 of the arm 1 and the projections 5 will bind against the flange and the casing, and a very 85 strong, rigid, and efficient connection between the casing and the arm will be secured.

The arm 1 is preferably made in one piece by stamping; and its outer end, opposite the end 4, will be bent laterally at 7; that is, downward with reference to the operative 90 position, of said arm; then longitudinally and away from the end 4, as at 8; then transversely (or upward) at 9, extending entirely across the body of the arm; and then reversely, toward the end 4, at 10. The portions 8 and 10 have threaded openings to receive means for attaching to the arm 1, a guide 11; and the arm 1 will have a projection 12, struck downward therefrom, adjacent to the portion 7, and perforated and 100 threaded to receive a pivot pin or journal to carry a finger or lever 13, with a forked end designed to coöperate with the guide 11.

In proximity to the projection 12 is another down turned projection 14, to serve as 105 a bearing for a rod or spindle 15, which projects into the casing 2. Between the bearing 14 and the outer end of the arm 1, the end of the spindle 15 will be bent laterally as at 16, to engage one end of the lever 13; and the 110 portion 7 will be shaped to provide a projection 17 against which the arm 16 will

force the lever 13, and which will therefore act as a stop for the lever 13, when required.

As stated, the arm 1 with the above-mentioned projections 5, 12, 14 and 17 will be produced by stamping, and formed by bending; and its faces and edges may be rounded, if desired, to give a finished appearance. On its lower face it will also have a couple of flats 18, with threaded holes for screws to secure below the arm in suspended relation to a member 19. This member has an opening above two horizontal slots, and is commonly known as a "staple." Its upper edge is bent over and is perforated to engage the flats to allow said screws to enter the arm 1. The staple, too, may be made by stamping and manufacturing in one piece.

When the casing 2 is applied to a knitting machine, it will always have a larger or smaller number of arms 1 affixed to the flange 3, and spaced equidistantly apart; the arms thus projecting radially outward from the casing. The spindle or rod 15 on each arm will be operated by a spring or the like inside the casing 2 to turn the spindle and cause the arm 16 to engage one end of the lever and force it as far as the stop 17 will permit; thereby maintaining the lever with its forked end in proximity to the guide 11. In that position one prong of the fork projects slightly beyond the curved top of the guide; hence the yarn 20 can be laid on this guide and allowed to slip down into the notch of the fork, and then be drawn to the needles as long as the machine continues running. After leaving the fork the yarn passes over a hook 21, fixed to the rod 15, and downward behind the staple 19 (Fig. 1), across the parallel slots therein. The casing or support 2 will be on top of another casing, not shown, but forming the lower part of the "stop-motion head"; and in this lower casing the devices for actuating the mechanism that suspends the operation of the knitting machine will be housed. The two casings will be fixed together and will constitute the head referred to; and this head is mounted on the central stem of the knitting machine, as above set forth. The devices in the lower casing are controlled by upstanding pivoted arms, located on the outside of the lower casing, adjacent the staples 19, and communicating with the inside of the lower casing. Each arm will have one or more lateral fingers, and there will of course be one of said arms below each arm 1, and associated with each staple 19. These fingers project through the slots of the staple, but are bent to be parallel with the opposite side; and the yarn will travel between them and the staple, holding the fingers and the arm carrying same in required position as long as the yarn remains intact. If tangled or knotted, however, the yarn will catch at

the fork and make it turn the rod 15 in such a direction that the hook 21 will permit the yarn to slip out of it; whereupon the yarn will no longer hold the fingers and the arm carrying same will withdraw them from the slots of the staple 19. To bring about this action, any suitable arrangement may be followed; and as a result, certain devices in the lower casing will be released and the stopping mechanism will come into play and suspend the operation of the machine till the trouble can be attended to. A break in the yarn will have the same effect.

The invention herein set forth relates mainly to the arm 1, with its bent end, its flats and its projections; and the devices inside the support or casing 2 and the lower casing, all of which are well known, and which operate in a manner familiar to those skilled in this art, form no part of same. The arm can be manufactured in quantities at low cost; and in case of injury can be replaced by a new arm at once, without the entire head requiring to be sent back from the textile establishment to the factory. 90

Another advantage afforded by our improved arm is the fact that it is stronger than an arm cast integral with the casing 2. It can accordingly be made somewhat smaller and shorter and thus reduce the over-all dimensions of the stop-motion head, especially if a large number of arms, such as twelve or sixteen, are to be carried by it to hold up the lines of yarn on their way to the needles. 95

The stop-motion head comprising the upper and lower casing is the part referred to above for carrying the devices to actuate the stopping mechanism; and these devices embrace not only what is inside the lower casing, but what is carried by the upper casing 2, as well. 100

Obviously one bolt or screw, as shown, or two separate bolts or screws, one for the portion 8 and the other for the portion 10, 110 can be utilized to mount the guide 11.

Having described our invention, what we believe to be new and desire to secure and protect by Letters Patent of the United States is:—

1. The combination with a support for thread-controlled stop mechanism, of an arm having one end to be secured to the support, and having its opposite end bent to extend laterally, then longitudinally, then transversely, and then reversely, to enable a thread guide to be secured to the arm at the points where said arm is bent longitudinally and reversely. 120

2. The combination with a support for thread controlled stop mechanism, having a thread guide, of an arm having at one end a projection stamped therefrom to abut the support, and having its opposite end bent laterally, then longitudinally, then trans- 130

versely, and then reversely to enable the thread guide to be mounted thereon at the points where the arm is bent longitudinally and reversely.

5 3. The combination with a support for a thread controlled stop mechanism having a spindle and a thread finger engaged by the spindle, of an arm having one end to be secured to the support, and having its opposite end bent laterally, then longitudinally, then transversely, and then reversely, to enable said finger to be mounted thereon at the points where the arm is bent longitudinally and reversely, said arm also having projections stamped therefrom adjacent said opposite end to serve as a bearing for the spindle and to receive a pivot for the finger, and a stop on the laterally bent portion of said arm in proximity to said projections to arrest the finger.

10 4. The combination with the casing of a thread-controlled stop mechanism having a spindle and a thread finger and comprising a casing having a flange thereon, of an arm

having a pair of projections struck therefrom, adjacent one end, and having an opening to receive a fastening member through said end to enable the arm to be secured to the casing with the projections abutting the edge of said flange, said arm having its opposite end bent laterally and longitudinally, then transversely, and then reversely, to enable a thread guide to be secured thereto at the points where the arm is bent longitudinally and reversely, said arm also having 35 projections stamped therefrom, one of which is perforated to form a bearing for the spindle and the other bored out to receive a pivot for the finger, and a stop on the laterally bent portion of said arm in proximity to 40 said last named projections to arrest the finger.

In testimony whereof, we have signed our names to this specification this 12th day of February, 1919.

EDW. H. STINES.
W. C. POTTER.
